UNITED STATES PATENT OFFICE.

MELVIN JINCKS, OF COHOCTON, NEW YORK.

BRIDLE-BIT.

No. 897,373.

Specification of Letters Patent.

Patented Sept. 1, 1908.

Application filed January 29, 1908. Serial No. 413,186.

To all whom it may concern:

Be it known that I, MELVIN JINCKS, a citizen of the United States, residing at Cohocton, in the county of Steuben and State of New York, have invented certain new and useful Improvements in Bridle-Bits, of which the following is a specification.

My invention relates to bridle bits for horses and has for its object the construction 10 of a bit to subdue fractious animals having two bars secured together by a link and with another link secured over the connecting link and adapted to engage the roof of the animal's mouth when the driving lines are drawn tightly, a pair of rings are loosely 15 mounted on the bit and secured at the two ends of the bridle nose strap to act as fulcrums for the bit bars.

The construction of my improved bit will 20 be described hereinafter and illustrated in the accompanying drawings in which—

Figure 1 is a front view of my improved bit, and Fig. 2, a view partly in section of the connecting link and the punishment link.

25 In the drawings similar reference characters indicate corresponding parts in both views.

The bars 1 of my improved bit are connected together by means of a link 2 and have 30 rings 3 secured in their ends to which the driving lines (not shown) are secured.

4 indicates other rings loosely mounted on the bars 1 to which are secured the ends of the bridle nose strap (not shown) so that said 35 rings 4 act as fulcrums for said bars 1 and when the ends of the bit are drawn back by the rings 3 the middle of the bit breaks at the link 2.

5 indicates a link secured to link 2 having 40 a cross-bar 6 and a curved bar 7 connecting the ends of the cross-bar, the link 2 being notched as shown at 2^a and the link 5 at 5^a, said notches engaging one another when the

link 5 is in position and prevent movement thereof relative to link 2.

When the bit breaks at link 2, as stated above, by drawing on the rings 3 the link 5 engages the roof of the animal's mouth and if a reciprocating motion is imparted to the bit by "sawing" on the lines the punishment 50 administered to the animal by the rubbing on the mouth is sufficient to subdue the most fractious animal.

Having thus described my invention what I claim is—

1. A bridle bit comprising two bars, a link 55 connecting the adjacent ends of said bars, a link having a straight cross-bar and a curved bar connecting the ends of said cross-bar, said links being correspondingly notched 60 where engaging each other to prevent movement of the links relative to one another, a ring secured to the free end of each of the bars aforesaid, and other rings loosely mounted on the bit between the end rings. 65

2. A bridle bit comprising the combination of two bars, a link connecting the adjacent ends of the bars having its middle portion externally notched, a link having a straight cross-bar and a curved bar connecting 70 the ends of said cross-bar, said last mentioned link being notched internally adjacent to the cross-bar aforesaid and mounted on the first-mentioned link so that the notches therein engage one another and the links are 75 perpendicular to one another, a ring secured to the free end of each of the bit bars, and other rings loosely mounted on the bit between the end rings.

In testimony whereof I hereto affix my 80 signature in the presence of two witnesses.

MELVIN JINCKS.

Witnesses:

M. A. McDowell,
T. B. Foote.
